INTERNAL ANCHOR DEVICE FOR WELLS

Irving J. Cox, Wilmington, Del., and Charles R. Johnson, Glenn Mills, Pa., assignors to E. I. du Pont de Nemours & Company, Wilmington, Del., a corporation of Delaware

Application August 10, 1939, Serial No. 289,378

6 Claims. (Cl. 166—13)

This invention relates to improvements in internal anchor devices for oil, gas, water, and other wells, such as are used to support torpedoes or other explosive devices or charges in operative position within the wells. The anchor device of the present invention is adapted particularly for selectively arresting the movement of torpedoes or other explosive devices upward or downward within the well, for temporarily plugging the well, or for sustaining the weight of one or more torpedoes secured to it.

Devices heretofore used for the purpose of plugging oil wells, or for supporting stemming material to close the bore of wells at predetermined points have comprised such means as are shown, for example, in the patents to Robinson 1,092,508, Fox 1,875,583, and Kingsley 1,979,802. The patent to McFadden 1,419,068 also shows an anchor means for supporting a load in a well while drilling.

An object of the present invention is the provision of an internal anchor device of the character specified which, when used for maintaining torpedoes or other explosive charges in position in the well, will, upon explosion of the shot, be broken to pieces and fall to the bottom of the well so as not to form obstructions therein.

A further object of this invention is a device of the character described which will be of light weight but at the same time capable of supporting the weight of 1 or more torpedo charges, or, in case of use for temporarily plugging a well, will support a substantial load of material.

Another object of the invention is the construction of an anchor mechanism which is not only economical but simple to manufacture and which will be not only reliable, but prompt and positive in its action in assuming an operative position in a well.

The foregoing objects are attained by a device of the character illustrated in the accompanying drawing showing a specific embodiment thereof, in which Figure 1 is a vertical elevation of the device presenting a portion in sectional view, and Figure 2 is a plan view showing the arms extended and in operative position to engage the walls of a well. Figure 3 illustrates a modified form of arm member or fluke.

Referring more particularly to Figure 1, A is a head or hub having a groove or pockets G circumferentially arranged intermediate its ends. B is a spider comprising a base member having a series of vertical posts or clevises C to which are pivoted arms D adapted to extend substantially radially when the lower member or spider B

comes to rest upon an obstruction such as charges of explosives previously seated in the well. The arms D are provided with lugs D¹ to engage in the pockets or groove G of the hub A so as to be actuated by the weight of the hub to bring the arms into operative position to engage the walls of the well or of the well casing when an obstruction is encountered, such as would indicate that the desired point for placing the anchor in the well has been reached.

As illustrated in Figure 1, the device is shown with the arms D in extended position to engage the side wall of the well to support the weight of a load above, or a charge of explosives suspended from it. In the event it is desired to use the bridge to prevent upward movement of the charge or series of charges in a well, or to prevent upward movement of sand or other material by pressure from below, the bridge need only be inverted when lowered in the well. In the inverted position, the weight of the spider B will cause the arms D to become extended, thus to engage the wall of the well or of the well casing to prevent upward movement. In this position, when pressure is applied from below against the hub or head A, such pressure serves to force the arms D into even more positive engagement with the walls of the well or of the well casing. While the necessity for removal from a well of an explosive charge, and coincident therewith the bridge or series of bridges for securing the charge in place, is infrequent, such removal occasionally becomes imperative and can easily be accomplished by the present invention by a pull on the head A when the bridge is in upright position, or by a pull on the spider B when the bridge is in inverted position in the well.

Operation.—The operation of the device will become apparent from the foregoing. The bridge is secured, for example, to a charge of explosives by means of the ears F, F, and is thus lowered into a well by means of a cable secured to the ears E, E. The weight of the load holds the elements A, B, in extended position, with the arms D closed, as shown in dotted position in Figure 1. When the charge reaches the bottom of the well, the pull on the cable connected to the head or hub A is thus released and the weight of the head bearing on the lugs D¹ of the arm D will force the arms D into extended position, as shown in Figure 2. With the bridge in this position the arms engage the walls or casing of the well sufficiently to support further charges of explosives or other load lowered from above to rest on the head or hub A.

Modification.—In some cases it may be desirable to provide a knuckle-joint in the arms D to permit free movement in one direction in the well without interfering with the proper operation of the arms to prevent movement in the reverse direction. This modification is shown in Figure 3, in which a spring member H is provided to bear against the pivoted portion to force it in to normal position.

Not infrequently shale, silt, or like material within the well, particularly below the casing, prevents the proper functioning of the elements of a mechanical device of the nature of the present invention. When it is essential to avoid the undesirable effects of such material on the proper operation of the anchor, particularly in raising the anchor and charge in the well, the modified form of arm shown in Figure 3 may be used. It will thus be seen that in any reverse movement of the anchor means by a pull on the head A, or otherwise, should the arms not fold in the normal position as indicated in the dotted position shown in Figure 1, the pointed ends of the arms DD will move downward against the springs H and thus offer no resistance. When the obstruction is passed, or in the event the anchor is again released to support the load carried below or above, the spring H will force the pointed end of the arms DD back to normal position as shown in the drawing to engage the wall or casing of the well.

From the foregoing the advantages of this invention for the purpose described are at once apparent. The device constructed in accordance with the embodiment illustrated in the accompanying drawing is simple but positive in its action and is constructed of a minimum of moving parts as contrasted with prior art bridges intended for similar purposes but involving complicated and costly mechanism which increase the opportunity for failures in operation. Since the function of such bridges is performed at great depth in wells and independent of outside aid or control, thus depending on automatic operation,

the positive action of the elements and simplicity of the parts of such a device is of paramount importance. The device is also suitable for use generally as a blasting plug in mining and blasting operations.

While we have described and illustrated herein a preferred embodiment of our invention, it will be apparent therefrom that various modifications thereof may be made without departing from the intended scope of our invention as represented by the following patent claims.

We claim:

1. An anchor device for wells comprising a hub, a spider slidably connected with the hub or head and having movable arms thereon operated by the hub upon relative sliding movement of the spider and the hub to move the arms into operative position for engaging the walls of the well.
2. An anchor device for wells comprising a hub, a spider slidably mounted on the hub and in collapsible relation therewith, movable arms secured to the spider and actuated to expandable position by the hub when the hub is being seated in the spider.
3. An anchor device for wells comprising a hub, a spider slidably mounted upon the hub, a series of arms pivotally secured to the spider and actuated by the hub upon sliding movement of the hub relative to the spider to open or close the arms.
4. An anchor device for wells comprising a hub, a spider slidably mounted upon the hub, a series of clevises secured to the spider, arms pivotally mounted on the clevises for engaging the walls of the well, and means on the hub for actuating the arms.
5. The anchor device of claim 1 in which the arms are knuckle-jointed intermediate their ends.
6. The anchor device of claim 2 in which the arms are knuckle-jointed intermediate their ends.

IRVING J. COX.
CHARLES R. JOHNSON.
